Primary Examiner — Robin V Webster(74) *Attorney, Agent, or Firm* — KMF Patent Services, PLLC; Kenneth M. Fagin, Esq.(57) **CLAIM**

The ornamental design for an aerator hub and aerator assembly, as shown and described.

DESCRIPTION

FIG. 1 is a perspective view of an aerator hub and aerator assembly showing our new design;

FIG. 2 is a front view thereof, the rear being identical;

FIG. 3 is a right side view thereof, the left being identical;

FIG. 4 is a top plan view thereof;

FIG. 5 is a bottom plan view thereof;

FIG. 6 is a perspective view of a second embodiment thereof;

FIG. 7 is a front view thereof, the rear being identical;

FIG. 8 is a right side view thereof, the left being identical;

FIG. 9 is a top plan view thereof;

FIG. 10 is a bottom plan view thereof;

FIG. 11 is a perspective view of a third embodiment thereof;

FIG. 12 is a front view thereof, the rear being identical;

FIG. 13 is a right side view thereof, the left being identical;

FIG. 14 is a top plan view thereof; and,

FIG. 15 is a bottom plan view thereof.

The broken line showing in the drawing view is included for the purpose of illustrating and forms no part of the claimed design.

1 Claim, 12 Drawing Sheets(56)
